CLAIM

The ornamental design for a rotatable holder for compact discs, CD-roms and other discs, as shown and described.

DESCRIPTION

FIG. 1 is a perspective view of a disc holder showing our new design, the series of disc boxes depicted by broken lines being for illustrative purposes only and forming no part of the claimed design;

FIG. 2 is a elevational view of the front side thereof, the rear side and right and left sides being the same in appearance;

FIG. 3 is a top plan view thereof; and,

FIG. 4 is a bottom plan view thereof.
